SAFETY MATCH AND FOLDER

Roy H. Myers, Ojai, Calif.

Application April 3, 1956, Serial No. 575,725

1 Claim. (Cl. 206—29)

This invention relates to match books of safety matches wherein matches are secured in a folding strip of material with a strip of abrasive material on the outer surface for striking matches withdrawn from the book, and in particular a cover formed of a continuous strip of material with a plurality of layers of matches extended from strips in which the igniting material forming heads of the matches is positioned on the ends of the strips secured in the folder or book with the stems of the matches extended to facilitate gripping matches as they are withdrawn from the folder.

The purpose of this invention is to eliminate the necessity of tearing stems of matches from match books wherein in numerous instances the stems are damaged to such an extent that it is substantially impossible to grip the match for striking.

With conventional match books or folders the heads of the matches are formed independently and the stems are secured by staples between a folded edge of a match book and the back thereof making it necessary to tear through a stem as a match is removed from the book. By this means it is difficult to grip a stem and in numerous instances the stems are bent or damaged as they are torn from the folder. With this thought in mind this invention contemplates a match book in which the position of matches therein is reversed so that the stems may readily be gripped between the thumb and forefinger of a hand and with the stem firmly held the match is readily removed from the folder and also readily ignited, by scratching the head over an abrasive substance on the outer surface of the book.

The object of this invention is, therefore, to provide means for forming a match book whereby heads of the matches, instead of the stems are bound in the book.

Another object of the invention is to provide a safety match folder in which heads of matches are secured under a flap on the outer surface of which an abrasive strip is provided.

Another important object of the invention is to provide an improved match book in which heads of the matches instead of the stems are secured below a flap having an abrasive thereon and in which an extended end of the book is adapted to be positioned below the flap having the abrasive thereon as a match is scratched for lighting whereby remaining matches of the book are protected from the fire resulting from ignition a match.

A further object of the invention is to provide an improved match book whereby stems of matches are extended to facilitate gripping in which the book is of a simple and economical construction.

With these and other objects and advantages in view the invention embodies a continuous strip of material, layers of material perforated and scored longitudinally to provide match stems, igniting material positioned on ends of the stems adjacent the perforations, a flap having an abrasive strip on the outer surface folded to cover the perforations and ends of the strips beyond the perfora-

2

tions and a staple for retaining the flap and layers of material scored to provide match stems in position upon the strip of material, said strip of material being provided with score lines whereby an extended end is adapted to fold below the flap through which the staple extends.

Other features and advantages of the invention will appear from the following description taken in connection with the drawing, wherein:

Figure 1 is a plan view of the improved match book showing the book with the parts in closed positions.

Figure 2 is an end elevational view of the improved match book.

Figure 3 is a plan view showing a blank strip of material with score lines therein to facilitate folding and showing the position of layers of material for forming matches in broken lines thereon.

Figure 4 is a plan view showing a layer of material formed to provide finished matches.

Figure 5 is a perspective view showing a layer of material for forming matches with the parts shown on an enlarged scale, and showing a blank before the igniting material forming the match heads is applied thereto.

Referring now to the drawing wherein like reference characters denote corresponding parts the improved match book of this invention includes a strip of material 10 having a score line 11 positioned to provide a flap 12, a score line 13 positioned to provide a hinged end 14 and a score line 15 positioned to provide a cover 16. The section between the score lines 11 and 13 provides a back 17 and layers of material 18 and 19 are positioned on the back and secured between the flap 12 and back 17 with a staple 20. The staple 20 extends through backing strips 21 and 22 of the layers 18 and 19, as shown in Fig. 2 and the backing strips are separated from stems 23 formed by parallel score lines or slots 24 with perforations 25.

The layers of material forming the matches are stamped, as shown in Fig. 5, with the perforations 25 at the ends of the score lines 24 whereby relatively narrow sections 26 are provided between the perforations and with the perforations comparatively close a stem may readily be broken from the layer of material by gripping the stem with the thumb and forefinger of a hand with the match book held in the other.

The ends of the stems 23 adjacent the perforations, are covered with a material adapted to be ignited by scratching forming heads 27 and with the layers of material positioned as shown in Figs. 2 and 3 the heads of the matches are secured below the flap 12 and with the parts in the closed position the end of the flap 16 is also extended below the outer edge of the flap 12.

A strip of abrasive material 28 is provided on the outer surface of the flap 12.

With the parts provided as disclosed and described the flap 16 is opened to expose the stems of the matches and with a stem gripped in one hand as the match book is held by the other the small section between the perforations is readily broken making it possible to remove

a match and after the match is removed from the folder the end of the flap 16 is inserted below the flap 12 and the match is scratched upon the abrasive strip 28. By this means the remaining heads of the matches are covered to prevent the heads being exposed to the fire of the burning match.

It will be understood that modifications, within the scope of the appended claim, may be made in the design and arrangement of the parts without departing from the spirit of the invention.

What is claimed is:

In a match book, the combination which comprises a strip of material having a portion forming a back with a

score line spaced from one end providing a flap and having spaced score lines spaced inwardly from the opposite end providing a hinged cover, a strip of abrasive material positioned on the outer surface of the flap, layers of material having registering perforations therein mounted on the back with the perforations positioned between the flap and back, said layers of material having cut lines extended from the perforations providing stems, and said stems having igniting heads thereon, the heads also being positioned between the flap and back and positioned closely adjacent the perforations, and a staple

10

extended through the flap and back and also through sections of the layers of material positioned between the perforations and ends thereof, the strip being of a length to extend over the stems and with its free end tucked beneath the flap.
